UNITED STATES PATENT OFFICE.

ABRAHAM BURGER, OF TORONTO, ONTARIO, CANADA.

SMOKER'S ASH RECEIVER.

Application filed February 3, 1927. Serial No. 165,717.

This invention relates generally to smoker's articles but more particularly to a receiver for smoker's waste, such as ashes, stubs and burnt matches.

5 One of its objects is the provision of a receiver of this character which will not only prevent the spilling and scattering of the waste over surrounding objects but which is so constructed, that, upon being deposited in 10 the receiver, the ignited stubs and matches will be quickly extinguished and the fire hazard be accordingly reduced.

Another object of the invention is to provide a simple and inexpensive ash receiver 15 which is neat in appearance, and which can be readily cleaned.

In the accompanying drawings:—

Figure 1 is a side elevation of an ash receiver embodying my invention. Figure 2 is 20 a top plan view thereof. Figure 3 is a cross section thereof on line 3—3, Fig. 2. Figure 4 is a similar view showing the cover of the receiver elevated to allow the waste to enter the waste-receiving chamber or receptacle.

25 Similar characters of reference indicate corresponding parts throughout the several views.

The waste receiver shown by way of example in the drawings, is of the type adapted to be placed on a table or other support, although it is to be understood that it may be embodied in other forms, such as a pedestal type of receiver.

30 The parts of the receiver are preferably stamped from sheet metal and they comprise a base constituting a receptacle or depository 10 in the shape of a cup or bowl, and a cover 11 applied to the receptacle and having 35 cigar, cigarette or pipe supports 12 attached to its marginal edge. The upper end of the receptacle is formed into a neck or collar 13 terminating in an outwardly-facing annular flange or shoulder 14. Rising centrally from the bottom of the receptacle is a substantially conical spreader member 15 which, serves to divert the waste downwardly and outwardly into the surrounding trough 16 of the receptacle. As shown in Figs. 3 and 4, the top of this spreader member is convex and terminates below the mouth of the receptacle. In its bottom, the receptacle has a weight 17 for stabilizing the device.

The cover 11 of the receiver has a depending rim or neck 18 telescopically or otherwise fitted in the corresponding neck 13 of 55 the receptacle 10 for permitting movement of said cover toward and from the conical spreader 15 thereof. Depending from the marginal rim of the cover is a waste-receiving funnel or tray 19 of inverted conical 60 form for directly receiving the ashes and other waste before they are finally deposited into the bottom of the receptacle 10. This tray depends a suitable distance into the receptacle and its bottom has a central discharge opening 20 therein. In the normal or lowered position of the cover, shown in Figs. 1 and 3, the discharge end of the tray 19 engages the top of the conical spreader 15, the latter thereby forming a seal or closure 65 70 for the former in such position. When the cover is raised to the position shown in Fig. 4, its discharge end is opened and any waste lodging in the conical part of the cover is thus allowed to drop into the receptacle. If 75 desired, the rim of the cover may be provided with an external flange 21 forming a hand-grip for facilitating raising it.

In the lowered position of the cover, the gaseous and ignited contents within the receptacle are effectively trapped and sealed 80 from the outside air and the obnoxious fumes are prevented from escaping into the room, and any ignited matches or stubs are quickly extinguished.

85 I claim as my invention:—

A smoker's ash receiver, comprising a bowl-shaped receptacle provided at its upper end with a neck terminating in an outwardly-facing annular flange and in its bottom 90 with a conical spreader terminating below the mouth of said receptacle, and a cover for the latter having a depending rim arranged to slidably fit within the receptacle-neck and provided at its upper end with an 95 external flange adapted for engagement with the receptacle-flange, said cover having an internal flange at its upper end terminating in a depending waste-receiving funnel disposed concentric with the cover-rim and normally resting at its open, lower end on the 100 top of said conical spreader.

ABRAHAM BURGER.
